UNITED STATES PATENT OFFICE

CLARENCE S. CRAZY, OF BURLINGAME, CALIFORNIA

SHINGLING MATERIAL

Application filed October 13, 1928. Serial No. 312,252.

My invention relates to improvements in shingling materials wherein a plurality of shingles are connected in a row by means of a flexible metal web whereby the shingles 5 may be rolled for storage and shipment and laid as a single continuous strip.

The primary object of my invention is to provide an improved shingling material.

Another object is to provide an improved 10 shingling material which will facilitate the laying of shingles.

A further object is to provide an improved shingling material formed in strips which 15 may be conveniently rolled for storage and shipment and which may be unrolled and laid as a continuous strip.

A still further object is to provide an improved shingling material which will be entirely fireproof and in which the shingles of a 20 row will be effectually held together.

I accomplish these and other objects by means of the improved device disclosed in the drawings forming a part of the present 25 application wherein like characters are used to designate similar parts throughout the specification and drawings, and in which—

Fig. 1 is a broken plan view of a portion 30 of a shingled surface showing the manner in which my improved shingling material is laid;

Fig. 2 is a broken plan view, partly in section of a strip of shingles showing the construction thereof;

Fig. 3 is a transverse section of a portion 35 of a strip; and

Fig. 4 is a transverse section of a portion of a rolled strip.

Referring to the drawings, the numeral 1 is used to designate a strip of flexible metal 40 webbing. A plurality of shingles 2 are arranged side by side in a row along the strip of webbing 1. The shingles 2 are preferably molded from fire-proof material such as asbestos, brick dust, or other non-inflammable material, the webbing being embedded within the molded shingles and connecting adjacent shingles to form a strip. The shingles may be shaped and colored in any desired manner to obtain an attractive appearance. Holes 3 are formed in the shingles

to admit nails for securing the shingles upon a surface such as a roof or wall.

The strips are made of a length such that each strip may be rolled, as indicated in Fig. 4 of the drawings, to make a roll of convenient size for storage and shipment. In laying the shingles, a roll of shingles is unrolled along the surface to be shingled and nails driven through the holes 3 to secure the shingles upon the supporting surface. Successive rows of shingles are laid with the shingles in staggered relation to the adjacent rows, and with the usual amount of lap. As each roll is unrolled, the shingles are extended in accurate alinement and in uniformly spaced relation across the roof or other surface to be shingled. The entire strip may thus be easily and quickly alined in the desired position and a workman may rapidly secure the strip and the individual shingles thereof, by driving nails through the holes 3 thus effecting a saving of time and labor. The webbing 1 may be easily severed between adjacent shingles to provide the required length of strip, and a shingle and the webbing embedded thereon may of course be severed to obtain a fractional part of a shingle at the end of a strip as necessary.

In addition to facilitating the laying of the shingles, the webbing serves to effectively retain the shingles in proper position upon the surface to which they are applied. Thus, in case the nails or other securing means applied through any particular shingle should rust away or otherwise be rendered ineffective, the webbing will effectively retain such a shingle in its proper position.

Having thus described my invention what I claim as new and desire to secure by Letters Patent is—

1. A shingling material comprising a plurality of shingles; and a flexible metal web embedded in said shingles and extending between adjacent shingles to connect the same side by side in a row whereby said shingles may be rolled for storage and may be unrolled and laid as a continuous strip.

2. A shingling material comprising a strip of flexible metal webbing; and a plurality of shingles molded in a row along said strip.

adjacent shingles being connected by said strip whereby the shingles may be rolled for storage and may be unrolled and laid as a continuous strip.

3. A shingling material comprising a strip of flexible metal webbing, and a plurality of shingles molded from fireproof material to embed the webbing and arranged in spaced relation and in a row along said strip, adjacent shingles being connected by said strip whereby the shingles may be rolled for storage and may be unrolled and laid as a continuous strip.

10 In witness whereof, I hereunto set my signature.
